TYPESETTING MACHINE COMPANY, OF NEW YORK, N. Y., A CORPORATION OF
NEW YORK.

LINE-COMPOSING MACHINE.

1,153,079.

Specification of Letters Patent.

Patented Sept. 7, 1915.

Application filed January 18, 1913. Serial No. 742,926.

To all whom it may concern:

Be it known that I, THOMAS S. HOMANS, a citizen of the United States, residing at Hempstead, in the county of Nassau and State of New York, have invented new and useful Improvements in Line-Composing Machines, of which the following is a specification.

This invention relates to improvements in line composing and type casting machines and more especially to those of the well known linotype class, and it is the object of the invention to provide an improved connection between the line delivery carriage or slide and its power-operated means whereby the line delivery carriage will be disconnected more readily and with greater certainty should the movement of the carriage become obstructed or the operation thereof interfered with in any way to impede or prevent its return to normal position.

The line delivery carriage serves to convey the line of matrices from the assembling elevator to the first elevator prior to presentation of the line of matrices to the line casting mold, and the present invention avoids damage either to the matrices or to other working parts of the machine in emergencies, such as those referred to above.

In the accompanying drawing: Figure 1 is a front view of a line delivery carriage and its operating means, the same embodying the present invention; Fig. 2 is a perspective view of the operating link for the line delivery carriage constructed in accordance with the present invention.

Similar parts are designated by the same reference characters in the several views.

The accompanying drawing shows the invention applied to line delivery mechanism of the type employed generally on machines of the linotype class, but it will be understood that the invention is not restricted necessarily to the particular construction shown, as equivalent structures may be used and they will be included within the terms of the claims at the end of this specification.

In the present instance, 1 represents the lever or arm which serves to reciprocate the line delivery carriage, this lever being fixed to a rock shaft 2. A spring 3 operates to swing the lever or arm 1 to the left, while a cam is usually employed to rotate the shaft 2 to swing the lever or arm 1 positively to the right and against the action of the

spring. The line delivery carriage is guided to reciprocate on the frame 4 of the machine and the line delivery carriage is composed usually of slidable blocks 5, 6, 7 and 8, a pair of downwardly projecting fingers 9 and 10 serving to receive each line of matrices between them and to convey the line of matrices from the assembling elevator to the first elevator in a manner well known to those skilled in the art. The blocks forming part of the line delivery carriage are connected by a longitudinal bar 11 whereby the elements of the carriage will reciprocate in unison.

Obviously, the construction of the line delivery carriage is not essential to the present invention and hence may be varied, that shown corresponding to the construction commonly employed. Experience has shown that the return movement of the line delivery carriage is apt to become obstructed or retarded from certain causes, such, for example, as where the line of matrices has not been properly removed, and the object of the present invention is to provide means whereby the line carriage will become disconnected automatically from its operating means, thereby preventing damage to the matrices, the carriage, or other parts of the machine which would otherwise result owing to the positive movement of the carriage operating means, and leaving the carriage in a position which will enable the operator to relieve the congestion.

The automatic disconnecting means may, according to the present invention, be constructed in different ways. In the present instance, it is embodied in the link which normally forms an operative connection between the line delivery carriage and its actuating lever or arm 1. The link 12 in the construction shown is provided at one end with a notch 13 to receive a pin 14 which latter is fixed to the line delivery carriage, and the link is provided with a pair of bearings or guides 15 and 16. A rod or bolt 17 extends through and is capable of longitudinal movement in the bearings 15 and 16, and this bolt is provided at one end with a head 18 which has a pin 19 fixed thereto, this pin having a pivotal engagement with the actuating lever or arm 1. The opposite end of the bolt or rod 17 is movable to and from a position across the opening presented by the notch 13, the notch in the present con-

struction presenting its opening toward the bottom of the link and when the end of the bolt 17 projects across the opening of the notch, it will lock or retain the pin 14 there-
5 in and thus prevent disconnection of the link relatively to the carriage. Preferably, the upper side of the bolt 17 opposite to the notch 13 is flattened to afford a suitable bearing for the lower side of the pin 14. The
10 wall 20 of the notch 13, which wall serves to transmit motion from the link to the line carriage in a direction to return the carriage to normal position, is beveled or inclined, as shown. A spring is employed
15 which serves normally to retain the bolt 17 in a position to lock the pin 14 in the notch 13. In the present instance, a coil spring 21 is provided which encircles the bolt 17, one end of this spring abutting against the bearing or guide 16 on the link and the other end of the spring abutting against a collar or shoulder 22 which latter is fixed to the bolt and is normally held by the spring against the bearing or guide 15 of the link. The
20 link, therefore, provides a positive connection between the line delivery carriage and its actuating lever or arm 1 when the latter is driving the carriage forward or to the left under the influence of the spring 3, but during
25 the return movement of the line delivery carriage by positive operation of the actuating lever or arm 1, the power is transmitted from the actuating lever to the line delivery carriage through the medium of the spring 30
30 21. Therefore, should the return movement of the line delivery carriage be retarded or checked from any cause, the continued movement of the actuating lever 1 will cause retraction of the bolt 17, this being permitted by compression of the spring 21. The tension exerted by the link on the line delivery carriage will tend to disengage the link from the pin 14 owing to the engagement of the pin with the beveled or inclined surface 20
35 of the notch, and when the bolt 17 has been retracted to a predetermined degree, its end opposite to the notch 13 in the link will have become retracted to a degree sufficient to permit escape of the pin 14 from the notch, 40 and the link will then be disconnected from the carriage and the carriage may remain stationary while the actuating lever 1 completes its movement.
45

The present invention provides an improved connecting device which automatically disconnects the line delivery carriage from its operating means when the tension on the carriage reaches a predetermined point, owing to the fact that the bolt 17
50 must be retracted to a predetermined extent before the parts are disconnected, and in the present construction, the tension required to disconnect the parts is not affected by the angle of the surface 20. It is advantageous
55 to employ a coil spring to retain the bolt in

normal position, as springs of that form can not only be made easily and cheaply, but it is comparatively easy to make all of the springs of the same tension for machines in use.

It is obvious that the link can be applied in a reverse position to that shown, that is to say, the notch and its locking bolt may be arranged to engage a pin on the actuating lever. Other equivalent constructions and arrangements may be used which are included within the scope of the claims.

I claim as my invention:—

1. In a machine of the linotype class, the combination of the line delivery carriage and means for operating the same, embodying a pin on one of the parts adapted to engage in a notch in the other part, and a bolt to normally lock the pin in said notch and operative to unlock the pin automatically by a relative movement between the carriage and its operating means.

2. In a machine of the linotype class, the combination of the line delivery carriage, a power-operated member for actuating the carriage, and means for connecting the carriage and said member, embodying a pin on one of the parts adapted to detachably engage a notch in another of said parts, and a spring-pressed bolt on one of said parts normally operative to retain the pin in said notch and movable into a position to unlock the pin by a relative movement between said member and the carriage.

3. In a machine of the linotype class, in combination with the line delivery carriage and its operating means, a connecting link carrying a spring-tensioned locking bolt, said bolt being movable longitudinally of the link and having an operating connection with one of said parts, said bolt being operative to break the connection between the said carriage and its operating means in event of the failure of the carriage to return.

4. In a machine of the linotype class, the combination of a matrix-carrying slide or carriage, a power-operated member for moving said slide, and a link connecting the slide to said member, comprising a portion notched to engage a pin or stud of one of said connected parts, a rod or bar attached to the other of said connected parts and adapted to move lengthwise of said link to close or open said notch, and a spring acting upon said rod portion tending to keep the notch closed.

5. In a machine of the linotype class, the combination of a line delivery carriage, a power-operated member for actuating it, one of said parts provided with a pin, and a connecting link provided with a notch to detachably receive said pin and carrying a spring-actuated bolt normally retaining said pin in the notch and operative to unlock the

pin by movement of said member relatively to the carriage.

6. In a machine of the linotype class, the combination of a line delivery carriage, an actuating lever, one of said parts having a pin, and a connecting link carrying a spring-actuated bolt connected to the other of said parts and movable relatively to the link, the latter having a notch to detachably receive 10 said pin, the movements of the latter serving to close and open said notch and thereby

normally lock said pin and release the same when relative movement occurs between said member and the carriage.

In testimony whereof I have hereunto set 15 my hand in presence of two subscribing witnesses.

THOMAS S. HOMANS.
